UNITED STATES PATENT OFFICE.

CHARLES A. DIES, OF CHICAGO, ILLINOIS, ASSIGNOR OF ONE-HALF TO JOHN V. LARSON,
OF CHICAGO, ILLINOIS.

LATHE-DOG AND THE LIKE.

1,333,707.

Specification of Letters Patent. Patented Mar. 16, 1920.

Application filed April 19, 1919. Serial No. 291,205.

To all whom it may concern:

Be it known that I, CHARLES A. DIES, a citizen of the United States of America, and a resident of Chicago, in the county of Cook, State of Illinois, have invented certain new and useful Improvements in Lathe-Dogs and the like, of which the following is a specification.

This invention relates to lathe-dogs and the like, in which a radially moving and screw impelled jaw is adapted to engage and hold cylindrical work within the ring shaped body member of the lathe-dog. And the present improvement has for its object to provide a simple and efficient structural formation and association of a lathe-dog parts, whereby dangerous projections on the exterior of the lathe-dog is avoided and a strong and substantial jaw actuating mechanism provided, all as will hereinafter more fully appear.

In the accompanying drawings:

Figure 1, is an elevation of a lathe-dog embodying the present invention.
Fig. 2, is a sectional elevation in perspective of the adjusting means of the tool.

Fig. 3, is a detail perspective view of the holding plate member.

Similar reference numerals indicate like parts in the several views.

Referring to the drawing, 1 represents the main body of the lathe-dog having the usual oval ring form shown, and provided at one end with a laterally extending prong 2 adapted for operative engagement with the face plate or other like part of a lathe. At the end opposite to the one carrying the prong 2, said main body 1 is formed with a tubular enlargement 3, the cylindrical bore 35 of which is disposed radially to the center of the work receiving opening of the lathe-dog, as shown, and adapted to contain the movable jaw actuating mechanism now to be described.

4 designates an operating sleeve arranged in the aforesaid circular bore of the tubular enlargement 3 of the lathe-dog body, and having at its inner end an external annular abutment flange or collar 5, adapted to bear against the inner end of said tubular enlargement 3, as shown. At its outer end, the operating sleeve 4 is formed with a square or like non-circular recess or orifice 6,

for operative engagement with a suitable hand wrench, by which forcible adjustment 55 of the parts is effected. Between said orifice 6 and the inner end of the sleeve 4, the bore thereof is screw-threaded for operative engagement with the radially moving jaw of the lathe-dog now to be described. 60

The radially moving jaw above referred to, comprises an outer cylindrical screw-threaded head 7 having operative engagement with the screw-threaded bore of the sleeve 4, aforesaid, and a square or like non-circular inner shank portion 8, of a less cross-sectional area than that of the head 7. In the present construction the non-circular shank portion 8 has movement in a correspondingly formed orifice in a plate member 70 9 disposed at the inner end of the operating sleeve 4, aforesaid, and fixedly held by the main body 1 of the lathe-dog, as shown.

With the above described construction a rotation of the operating sleeve 4, is adapted to impart radial movement to the gripping jaw 7, 8, aforesaid, in that the shank 8 of said jaw is held from rotation with said sleeve 4, by the holding plate 9, aforesaid.

10 designates a milled collar, having a 80 drive fit on the outer end of the operating sleeve 4, and abutting against the main body 1 of the lathe-dog, to hold said operating sleeve in place. In addition, said collar provides means for an initial operation of the 85 parts by the fingers of the operator in applying the lathe-dog to the work, and in a final operation of removing the lathe-dog from said work.

Having thus fully described my said invention what I claim as new and desire to secure by Letters Patent, is:—

1. In a tool of the type described and in which an operating sleeve is revolvably mounted in the tool body and is formed with a screw-threaded bore, the combination of a non-revolute jaw member formed with a non-circular shank and an enlarged screw-threaded end portion engaging the bore of said operating sleeve, and a separate plate 100 member attached to the tool body at an end of the operating sleeve and having a non-circular guide orifice for the shank of the jaw member.

2. In a tool of the type described and in 105 which an operating sleeve is revolvably

mounted in the tool body and is formed with a screw-threaded bore and with fixed abutment collars at each end, the combination of a non-revoluble jaw member formed with a non-circular shank and an enlarged screw-threaded end portion engaging the bore of said operating sleeve, and a sepa-

rate plate member attached to the tool body at an end of the operating sleeve and having a non-circular guide orifice for the shank 10 of the jaw member.

Signed at Chicago, Illinois, this 12th day of April, 1919.

CHARLES A. DIES.
